(73) Assignee: **Sony Corporation**, Tokyo (JP)

“Broadcast/Production System General Catalog 2000—
NTSC/PAL.SECAM” p. 104; Sony Corporation, 1999.

(**) Term: **14 Years**

* cited by examiner

(21) Appl. No.: **29/131,403**

Primary Examiner—Nanda Bondade

(22) Filed: **Oct. 23, 2000**

(74) Attorney, Agent, or Firm—Rader, Fishman & Grauer

(51) LOC (7) Cl. **14-01**

CLAIM

(52) U.S. Cl. **D14/167**; D14/135

The ornamental design for a data recording and editing
control unit, as shown and described.

(58) Field of Search D14/135, 136,

DESCRIPTION

D14/156, 157, 160–162, 167–168, 188,
197–198; 369/75.1, 75.2, 77.1, 77.2
